UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed April 4, 1925. Serial No. 20,848.

To all whom it may concern:

Be it known that I, DAVID S. KENNEDY, a citizen of the United States, residing at Brooklyn, in the county of Kings, State of New York, have invented certain new and useful Improvements in Typographical Distributing Machines, of which the following is a specification.

The invention relates to typographical distributing machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In some machines, such as the commercial model 9, where matrices may be drawn from several magazines and mixed together in the same line, the distributing mechanism includes a primary distributor, which first sorts the matrices according to font, and a plurality of main distributors which thereafter sort the matrices of the individual fonts according to character and restore them to their proper channels in the magazines. With this type of distributing mechanism, the matrices, after font separation, pass down chutes or tubes and enter so-called lower distributor boxes, from which they are fed one at a time to the main distributors under the control of reciprocating pawls or escapements. In order that these pawls or escapements may cooperate properly with the matrices, the latter are provided in their bottom edges with central notches, which necessarily vary in shape and depth according to the thickness of the individual matrices. Besides adding to the cost of production, such notches in the matrices materially limit the space ordinarily required for the regular font notches and, moreover, seriously weaken the matrices, especially when the latter are formed with other necessary cuts or notches. Furthermore, matri-

ces comprising fonts used on other machines, such as those of the single distributor class, are excluded from use on machines of the multiple distributor class described, since they do not have the required central notches.

The pending application of John R. Rogers, Serial No. 690,683, is directed to certain improvements whereby the distributing mechanism is capable of handling matrices of all fonts whether they have or have not the objectionable central notches referred to. According to these improvements, each of the lower distributor boxes, instead of being equipped with a pair of reciprocating pawls or escapements, as customary, is provided with a matrix lifting finger and a cooperating pusher member, the former acting to feed the matrices, one at a time, to the overlying main distributor, and the latter acting by its engagement with the projecting ears of the matrices to advance them into the range of action of the lifting finger.

The present invention is directed to various improvements in a distributor box of this particular type, although some of them may be advantageously employed in boxes of other types. These improvements will best be understood from the detailed description to follow.

In the accompanying drawings, the invention has been shown merely in preferred form and by way of example and as applied to the specific type of distributor box indicated. However, many changes and variations may be made therein and in its mode of application, which will still be comprised within its spirit. It is to be understood, therefore, that the invention is not limited to any specific form or embodiment, except in so far as such limitations are specified in the claims.

Referring to the drawings:

Fig. 1 is a side elevation, partly broken away, of the improved distributor box;

Fig. 2 is a vertical transverse section, taken on the line 2—2 of Fig. 1;

Fig. 3 is a view, similar to Fig. 1, with one of the box side plates removed, and showing the pusher member in its retracted position;

Fig. 4 is a detail horizontal section, taken on the line 4—4 of Fig. 3;

Fig. 5 is a perspective view of the matrix pusher member detached; and

5 Figs. 6 and 7 are detail views of the pusher cam, Fig. 7 being a section on the line 7—7 of Fig. 6.

The matrices X are dropped by the primary distributor (not shown) into tubes or chutes A¹ and enter one or another of the lower distributor boxes B, through which they are guided in upright position by their projecting ears x upon the upper and lower inclined rails B¹. The rails of each box are formed with matrix arresting shoulders B² rising from the horizontal portions B³, and have the customary extensions B⁴ arranged directly beneath the receiving ends of the corresponding main distributor, the latter comprising, as usual, the longitudinally ribbed bar C and set of matrix conveying screws C¹. Each of the boxes is equipped with a reciprocating matrix pusher member D and a matrix lifting finger E, the pusher member being constructed and arranged to engage the matrices by their four projecting ears x and acting to deliver them forwardly in a vertical position, without danger of tilting or displacement, to a point where they are engaged by the lifting finger and lifted thereby into the threads of the distributor screws C¹. The pusher member D and lifting finger E are both controlled from a cam shaft F⁴ driven by the spindle C² of one of the distributor screws C¹, so as to operate in perfect synchronism in feeding matrices to the distributor, the cam shaft being aligned with the screw spindle and connected thereto by a clutch J, which permits the ready removal and replacement of the distributor box. An edge or peripheral cam F⁵, fixed to the shaft F⁴ and engaging a roller E⁴ of a spring rod E³, actuates the lifting finger E through a rocking lever E¹ and a return spring E². The operating connections for the pusher member will subsequently be described. The head portion of the pusher member D is constructed to present four ear engaging blocks arranged in upper and lower pairs and having their forward edges aligned in the same vertical plane, the blocks D² of the upper pair being carried on the forward ends of bracket plates D⁴ and arranged to engage the matrices by their upper projecting ears, and the blocks D³ of the lower pair being connected directly to the pusher member and arranged to engage the matrices by their lower projecting ears. The upper and lower guide rails B¹ are notched or slotted at B⁵ to accommodate the pusher blocks D², D³, which move horizontally across the inclined portions of the rails. Normally, the upper edges of the

pusher blocks are disposed in the path of the gravitating matrices and check them by their projecting ears in the dotted line position shown in Fig. 1, but when the pusher member is retracted, the blocks are drawn within their respective slots B⁵ beneath the inclined portions of the rails B¹ (see Fig. 3), and the matrices arrested by the blocks are then free to drop onto the horizontal portions B³ of the rails, where they are immediately subjected to the action of the pusher blocks and advanced thereby solidly and squarely up against the arresting shoulders B². At this point, the matrices are lifted by the finger E clear of the arresting shoulders and into the threads of the conveying screws C¹, which carry them forwardly along the upper edges of the extensions B⁴ and into engagement with the distributor bar C. A separator blade G, which is customarily used in connection with a lifting finger, is also provided and, besides performing its normal function of keeping succeeding matrices in place while the leading one is being lifted, it serves coordinately with the lower portion of the upper rail 90 adjacent the lifting finger to prevent forward tilting or displacement of a matrix while supported by the blocks D² as the latter move toward the arresting shoulders B². The foregoing parts and their mode of operation, except as hereinafter pointed out, are or may be the same as those embodied in the Rogers application before mentioned. The improvements, to which the present invention is directed, will now be taken up 100 and described in detail.

First, it may be noted that the pusher member, in the present instance, is formed with a shank portion D¹ extending rearwardly from the head portion and slidably mounted in fixed bearings B⁷, B⁸ rising from the base plate B⁶ of the distributor box. The pusher member may thus be properly guided and sustained in its reciprocating movements independently of the head portion, which latter is made free or floating, clearance enough being allowed between the entire head portion (including the bracket plates D⁴, the pusher blocks D², D³ and the supporting nose D⁵) and the adjacent surfaces of the distributor box to provide for such a floating fit. This arrangement not only simplifies the manufacture of the parts but also greatly improves their operation, since the slide bearings for the pusher member, which of course require a certain amount of lubrication, are sufficiently spaced from the course traversed by the matrices that any danger of oil reaching the latter is eliminated. In this connection, it will be understood that the matrices should be kept as clean as possible and particularly free from oils or lubricants of any kind,

which latter quickly collect dust and dirt and seriously interfere with proper handling of the matrices.

Next, it is pointed out that the operating connections for the pusher member D comprise a lever F of the third order pivoted at its upper end to the distributor box and forked at its lower end to engage a pin protruding transversely from the shank 10 portion D¹. Between its ends, the lever F is provided with a roller F¹ arranged to be engaged by a face cam F² keyed to the shaft F⁴ and which serves to actuate the pusher through the connections just described. An extension spring F³, anchored to the slide bearing B⁷ and connected below the roller F¹ to the lever F, tends to keep the roller in constant engagement with the face of the cam F² and acts through 15 said lever to move the pusher member forwardly when permitted by said cam. With this arrangement and due in part to the character of the lever F and the size and type of cam employed, the reciprocation of 20 the pusher member D is carried out smoothly and easily and with little wear on the moving parts. Furthermore, the cam shaft F⁴ is supported with the greatest degree of rigidity for withstanding the strain 25 to which it is subjected, by an outer bearing B¹⁰ arranged preferably between the cams F² and F⁵.

Means are also provided for effecting a relative adjustment between the cam F² 30 and the operating lever F, in order that the stroke of the pusher member D may be accurately determined and maintained within the required limitations, it being understood that in the extreme forward position 40 of the pusher, the blocks D², D³ should just clear the matrix arresting shoulders B²; otherwise the blocks would bank against the shoulders when the box was running idly and cause unnecessary noise and probable burring of the shoulders. At the 45 same time, it is important that such clearance be sufficiently restricted so that matrices of minimum thickness will be delivered solidly against the arresting shoulders by 50 the pusher member. Accordingly, the pusher cam F² is mounted for axial adjustment on the shaft F⁴ and, in the embodiment shown (see Figs. 6 and 7), it is formed with a radial notch or slot F⁶ to receive 55 a key pin F⁷ projecting from the shaft, a set screw F⁸ being provided to hold the cam in its adjusted positions. Thus, at the time of the initial setting of the pusher, or in the event of wear upon the parts, it 60 is simply necessary to loosen the set screw F⁸ and shift the cam F² to the required point, the slot F⁶ being sufficiently deep to permit the adjustment. Since the thrust will always be in a forward direction 65 against the outer face of the cam, it is pro-

posed to interpose shims or very thin washers F¹⁰ between the cam and bearing B¹⁰ (as shown in Figs. 1 and 3) so that the latter may take the thrust, instead of relying solely upon the set screw F⁸. 70

Referring now to the clutch J, which permits the ready removal and replacement of the distributor box, the driven member J¹ is mounted in the end of the shaft F⁴, so as to yield rearwardly against the tension of a 75 spring J³ seated behind it, a pin and slot connection J⁴ being employed to key said member to the shaft and permit the relative movement desired. The driving member J² is fastened to the end of the screw spindle 80 C² and is provided with an aligning sleeve J⁵, which is arranged to surround the two members when properly engaged. Accordingly, the clutch is adapted to pick up automatically or become engaged without manual attention whenever the box is replaced in operative position. As a further feature, the engaging surfaces of the two clutch members are beveled or wedge-shaped as at 85 J⁶, which feature not only facilitates their engagement, but, since the spring J³ acts constantly to press the said surfaces together, a tight joint is maintained at all times irrespective of wear. In this way, any relative rotary displacement of the two 90 clutch members is obviated and the required relation between the cam shaft F⁴ and the distributor screws C¹ is always maintained. The aligning sleeve J⁵ prevents any lateral 95 separation of the clutch members due to the wedging action of their beveled surfaces.

Means are further provided for guiding the lifting finger E, so that its initial purchase on the bottom edge of a matrix will be gradually increased as the latter is lifted 100 above the arresting shoulders B². An arrangement of this kind is very advantageous since the extent of the finger's engagement with a matrix at the start ordinarily does not exceed .027"—an extent determined by the 105 thickness of the thinnest matrix—and there is more or less danger of a matrix slipping off the top of the finger before it becomes engaged by the distributor screws. Such means, according to the present invention, 110 consist of a pair of blocks K fastened to the inner walls of the lower rail extensions B⁴ and formed with inclined surfaces K¹, which serve to guide the lifting finger in the desired path. An adjusting screw E⁵, 115 having a threaded engagement with the finger E and projecting outwardly from one of the side faces thereof, is formed with a head E⁶ convexed on its under side to fit a corresponding recess in a small wear plate 120 E⁷ (see Figs. 3 and 4). The wear plate E⁷ has a sliding engagement with the guiding surfaces K¹, against which it is held by the screw E⁵ under the tension of a spring E⁸ anchored to the rocking lever E¹ and con- 125 130

5 nected to the opposite side face of the lifting finger E. It will now be seen, as a result of this arrangement, that as the lifting finger is moved upwardly, 10 the wear plate E⁵ is caused to follow the inclined surfaces K¹, the socket bearing between said plate and the screw head E⁶ allowing the latter to adapt itself to the inclination of said surfaces. In this way, the 15 finger is made to swing inwardly beneath the matrix being lifted to an extent determined by the degree of inclination of the guiding surfaces K¹, or for a distance sufficient to prevent the matrix slipping off the 20 top edge of the finger. Furthermore, the arrangement provides for a convenient adjustment of the lifting finger in setting or resetting it in operative position, it being simply necessary to turn the screw E⁵ one 25 way or the other to move the finger toward or from the guide blocks K, which action will change its relation to the arresting shoulders B² and determine its initial purchase on the matrices.

30 25 While, as above stated, the foregoing improvements are particularly useful in connection with a "gravity box" of the kind covered in the pending application of John R. Rogers before referred to, they or some 35 of them may advantageously be applied to distributor boxes of other kinds. For instance, the improvements made in the clutch between the cam shaft F⁴ and the screw spindle C², or those made in respect to the lifting finger E, would be readily applicable to the ordinary "lift box" and would function in substantially the same way as herein described.

Having thus described my invention, its 40 construction and mode of operation, what I claim and desire to secure by Letters Patent of the United States, is as follows:

45 1. In a typographical distributing machine, the combination of a distributor box through which the matrices pass by gravity, a matrix lifting finger, a reciprocating pusher member for advancing the matrices into the range of action of the lifting finger, and adjusting means to regulate the stroke 50 of the pusher member.

55 2. In a typographical distributing machine, the combination of a distributor box through which the matrices pass by gravity, a matrix lifting finger, a reciprocating pusher member for advancing the matrices into the range of action of the lifting finger, a cam-actuated lever for operating the pusher member, and means for effecting a 60 relative adjustment between said lever and its actuating cam to regulate the stroke of the pusher member.

65 3. In a typographical distributing machine, the combination of a distributor box through which the matrices pass by gravity,

a matrix lifting finger, a reciprocating 65 pusher member for advancing the matrices into the range of action of the lifting finger, a constantly driven shaft, and a cam secured thereto for actuating the pusher member, the said cam being adjustable on the 70 shaft to regulate the stroke of the pusher member.

4. In a typographical distributing machine, the combination of a distributor box through which the matrices pass by gravity, 75 a matrix lifting finger, a reciprocating pusher member for advancing the matrices into the range of action of the lifting finger, a constantly driven shaft, and a face cam secured thereto for actuating the pusher member, the said face cam being adjustable 80 axially on said shaft to regulate the stroke of the pusher member.

5. In a typographical distributing machine, the combination of a distributor box 85 through which the matrices pass by gravity, a matrix lifting finger, a cooperating matrix pusher member, a peripheral cam for actuating the lifting finger, a face cam for actuating the pusher member, a shaft 90 whereon the cams are mounted, and bearings for said shaft, one arranged between the two cams, for the purpose described.

6. In a typographical distributing machine, the combination of a distributor box 95 through which the matrices pass by gravity, a matrix lifting finger, a reciprocating pusher member for advancing the matrices into the range of action of the lifting finger, a spring controlled lever of the third order 100 connected to the pusher member, and a constantly driven face cam for actuating said lever.

7. In a typographical distributing machine equipped with matrices formed with projecting ears, the combination of a distributor box, a matrix lifting finger, a reciprocating pusher member to advance the matrices into the range of action of the lifting finger, said pusher member having a 110 floating head portion constructed to cooperate with the projecting ears of the matrices, and means for guiding and sustaining the reciprocating pusher member independently 115 of its head portion.

8. In a typographical distributing machine equipped with matrices formed with projecting ears, the combination of a distributor box, a matrix lifting finger, a reciprocating pusher member to advance the 120 matrices into the range of action of the lifting finger, said pusher member consisting of a floating head portion constructed to engage the matrices by their projecting ears and a shank portion projecting rearwardly 125 therefrom, and fixed bearings wherein the shank portion is sustained and guided.

9. In a typographical distributing ma-

chine including a distributor bar and a set of constantly driven matrix conveying screws, the combination of a removable distributor box, and means for feeding matrices therefrom to the screws, including a cam shaft mounted in the box and aligned with one of the screw spindles, a clutch comprising a driving member screwed to the screw spindle and a driven member keyed to the cam shaft, and a sleeve carried by one of said members to hold them in proper alignment when engaged.

10. In a typographical distributing machine including a distributor bar and a set of matrix conveying screws, the combination of a distributor box, and means for feeding the matrices therefrom to the screws, including a cam shaft driven by one of the screw spindles, and a driving clutch arranged between said shaft and screw spindle, the said clutch comprising a driving member and a driven member having their engaging portions correspondingly beveled to prevent relative rotary displacement when engaged.

15. 11. In a typographical distributing machine including a distributor bar and a set of matrix conveying screws, the combination of a distributor box, and means for feeding the matrices therefrom to the screws, including a cam shaft driven by one of the screw spindles, and a driving clutch arranged between said shaft and screw spindle, the said clutch comprising a driving member and a driven member having their engaging portions correspondingly beveled, and an aligning sleeve surrounding said members when engaged.

20. 12. In a typographical distributing machine including a distributor bar and a set of matrix conveying screws, the combination of a distributor box, and means for feeding the matrices therefrom to the screws, including a cam shaft driven by one of the screw spindles, and a driving clutch arranged between said shaft and screw spindle, the said clutch comprising a beveled driving member and a correspondingly beveled driven member, one spring-pressed toward the other, for the purpose described.

25. 13. In a typographical distributing machine including a distributor bar and a set of matrix conveying screws, the combination of a distributor box, and means for feeding the matrices therefrom to the screws, including a cam shaft driven by one of the screw spindles, and a driving clutch arranged between said shaft and screw spindle, the said clutch comprising a beveled driving member and a correspondingly beveled driven member, one spring-pressed toward the other, and an aligning

sleeve surrounding the clutch members when engaged.

30. 14. In a typographical distributing machine including a distributor bar and a set of matrix conveying screws, the combination of a distributor box, a reciprocating finger for lifting the matrices successively into the threads of the conveying screws, and means for guiding the finger in its reciprocating movements, said guiding means being arranged to permit a facewise movement of the finger during its upstroke for increasing its purchase on the bottom edge of a matrix being lifted.

35. 15. In a typographical distributing machine including a distributor bar and a set of matrix conveying screws, the combination of a distributor box, a reciprocating finger for lifting the matrices successively into the threads of the conveying screws, means for guiding the finger in its reciprocating movements, and means for adjusting the finger facewise in relation to said guiding means, for the purpose described.

40. 16. In a typographical distributing machine including a distributor bar and a set of matrix conveying screws, the combination of a distributor box, a spring controlled reciprocating finger for lifting the matrices successively into the threads of the conveying screws, inclined guiding surfaces adjacent the finger, and an adjusting pin or screw carried by the latter and engaging said guiding surfaces.

45. 17. In a typographical distributing mechanism, comprising a distributor bar and a set of matrix conveying screws, the combination of a vertically reciprocating finger for lifting the matrices successively into the threads of the screws, and means for imparting a sidewise movement to said finger during its upstroke to increase its purchase on the bottom edge of the matrix being lifted.

50. 18. In a typographical distributing mechanism, comprising a distributor bar and a set of matrix conveying screws, the combination of a distributor box through which the matrices pass by gravity, a vertically reciprocating finger for lifting the matrices successively into the threads of the screws, and means for arresting the matrices in the path of the finger, the latter being arranged to move sidewise during its upstroke to increase its purchase on the bottom edge of the matrix being lifted.

55. In testimony whereof, I have affixed my signature hereto.

DAVID S. KENNEDY.
